UNITED STATES PATENT OFFICE.

JAMES SMITH, OF CHICAGO, ILLINOIS, ASSIGNOR TO NEW PROCESS COPPER CASTINGS COMPANY, A CORPORATION OF DELAWARE.

PROCESS AND APPARATUS FOR CASTING BOSH PLATES.

Application filed November 24, 1919. Serial No. 340,335.

To all whom it may concern:

Be it known that I, JAMES SMITH, a citizen of the United States, and residing in the city of Chicago, county of Cook, and State 5 of Illinois, have invented or discovered new and useful Improvements in Processes and Apparatus for Casting Bosh Plates, of which the following is a specification.

My invention consists in a new and improved process and apparatus of casting bosh plates for furnaces, and said process more particularly consists in casting said plates in a vertical position, the sand core being supported, on an integral sand base, 10 within the sand mold, whereby the use of anchors or other supports or reinforcement for the core is avoided.

Bosh plates are now cast horizontally, and therefore the core must be supported within 20 the sand mold by means of metal anchors which remain embedded in the casting and weaken the same. Furthermore wires are introduced into the sand mold to strengthen it and prevent buckling during the casting 25 operation. These wires are withdrawn after the metal has been poured, leaving holes in the internal baffles which disturb the water currents and therefore impair the efficiency of the bosh plates.

I also show new and useful improvements 30 in the patterns used for moulding in my improved process.

Other novel features of construction and arrangement of parts will appear from the 35 following description.

In the accompanying drawings, which are merely intended to illustrate the principles of my invention without limiting the scope of the same, Fig. 1 is a vertical section, taken 40 along the line I—I in Fig. 2, showing the sand mold and core assembled in the flask ready for the pouring; Fig. 2 is a section taken along the line II—II in Fig. 1; Fig. 3 is a perspective of a type of bosh plate cast 45 by my improved method; Fig. 4 is a section taken along the line IV—IV in Fig. 5, showing the flask assembled, ready to first form the nose of the sand mold and later the body of the same; Fig. 5 is a similar 50 view taken along the line V—V in Fig. 4; Fig. 6 is a plan view of the combined core box and base box, showing the sand filled therein, the top wall of the base box being removed to more clearly show the structure; 55 Fig. 7 is a longitudinal section taken along

the line VII—VII in Fig. 6; Fig. 8 is a detail showing the inner or upper face of the sand base and the gate formed therein to connect the sprue with the mold cavity for the admission of the metal; Fig. 9 is a front 60 view of the wooden pattern plate which is used to form the mold cavity for the front wall of the bosh plate; Fig. 10 is an end view of one of the split sand molds for the handles, and Fig. 11 is an inner face view of 65 one of the said mold parts.

The following is a detailed description of my process as the same is illustrated in the accompanying drawings, reference being first had to Figs. 1, 2 and 3. 70

The flask is composed of a drag A, a cheek B mounted on said drag, and a cope C mounted on said cheek. The elements are detachably clamped together by means of their pierced ears 1 and bolts 2. The drag 75 A is provided with supporting feet 3 and slots or apertures 4 in its bottom for the escape of gases from the molten metal.

The sand mold, which determines the outside contour of the bosh plate is composed 80 of two parts, the body part D and the nose part D'. The body D is formed in the cheek B and extends to the top of the same, while the nose D' is formed in the cope. E is the sand core which is inserted up into the 85 sand mold D—D', and F is the sand base which occupies the drag A and is integrally connected to the core E.

The form of the bosh plate G, which is shown in Fig. 3, is shown simply as an illustration, as any character of bosh plate may be cast by my process. The interior structure of the plate is indicated in dotted lines, 5 being the baffles which direct the flow of water through the plate from the inlet 90 port 6 to the outlet port 7 or 8, according to the particular furnace practice. 9 are the loop handles integral with the front of the bosh plate to facilitate its removal from the bosh of the furnace. 95

I will first describe the operation of forming the sand mold D—D', referring especially to Figs. 4 and 5. 10 is a wooden block fitting in the drag A upon which is mounted the wooden core pattern 11 whose foot may 100 be stepped in a socket in said block 10. The other end or nose of said pattern is separate, being a nose piece 12 which may be connected to the body pattern 11 by means of dowels 13. 105

14 is the wooden sprue pattern whose end is stepped in a socket in the block 10. The pattern 14 extends a little above the top of the cope C, and the top of the 5 pattern 11 is level with the top of the cheek B. I first insert the block 10 into the drag, and then mount thereon the patterns 11 and 14. The cheek B is then put down in place and bolted to the drag. A steel plate H 10 is then placed over the top of the cheek, said plate being properly apertured to permit the upward extension of the dowels 13 and the sprue pattern 14. Said plate is also provided with holes which register with the 15 holes in top ears 1 of the cheek. The cope is now put in place and bolted to the plate H and the cheek. The nose pattern 12 is now placed on the plate H in registration with the pattern 11 with which it is connected by the dowels 13 extending up 20 through the plate H.

The molder's sand is now introduced into the cope C, the curved riser patterns 15 being installed to form the riser passages 25 in the sand mold. The cope is now rammed, or jarred by placing the flask on a machine. The top bolts 2 are now removed and the plate H with the cope and its contents lifted off, the pattern 14, which remains with the 30 cheek and drag, leaving a vertical hole in the nose mold forming the upper part of the sprue. The nose mold thus formed is set aside to harden. The molder's sand is now filled into the cheek about the sprue and 35 core pattern and the flask is rammed or jarred. The cheek is then detached from the drag and lifted off and set aside.

When the sand mold parts in the cope and cheek are hardened, the wooden patterns 40 are removed.

My reason for forming the sand mold in two parts is that by this means I am able to more properly compact the sand, as the attempt to compact the sand mold in one 45 piece and operation would result in irregular density and adhesion.

I will next describe the formation of the sand core E and its supporting base F. For this purpose I use a wooden core box I and 50 integral therewith a wooden base box J.

The core box is of the following construction. Its top is open while its bottom 55 is curved to give the desired contour to the core. The inner end and sides of the core are defined by the permanent walls 17 and 18, respectively, the outer ends of the walls 18 being connected by the detachable pattern plate 19 which defines the front of the core and which is mounted in place by 60 means of dowels engaging the bottom 16. Said plate 19 is provided with three transverse ports or openings 20 which correspond to the ports 6, 7 and 8 in the front of the bosh plate. To enable the plate 19 to be 65 lifted away from the finished sand core

without rupturing the necks of sand which connect the core E to the base F through the openings 20, I form one side of said openings of wooden insert blocks 21 held in place by dowels 22, which blocks can be removed 70 before the plate 19 is lifted out.

The internal baffles or partitions 5 of the plate are provided for in the sand core by means of wooden strips 23 temporarily mounted on the bottom 16 by means of 75 dowels.

The base F is formed in the box J, which may conveniently be attached to or formed as an extension of the box I. The box J extends above and below the level of the box I 80 to provide the proper width for the base which fits the drag A. Said box has a permanent front wall 24, and top and bottom walls 25, the former being removable to permit of the discharge of the base from 85 the box. 26 represents side boards which hold the sand during the compacting operation. The top wall 25 and the adjacent side board 26 are removed when the core and base are to be removed from the boxes I 90 and J.

The molder's sand is filled into the boxes I and J, the top of the box I being struck off at the tops of the strips 23, the walls 17 and 18 and the plate 19 being exposed. 95 In filling the box J wooden blocks 27 are placed against the front of plate 19 their other ends reaching to the front wall 24, to provide apertures for the later insertion of the small sand molds for the handles 9. 100 Also wooden prints are also placed against the front of the plate 19 to form the gate passages 28, Fig. 8, which connect the mold cavity with the lower end of the pouring sprue formed by the pattern 14. 105

After the boxes I and J are filled, the sand is compacted by ramming or jarring and the boxes are then turned upside down to discharge the integral sand core and sand base upon a metal plate. The wooden pattern members are now lifted out and the core and base are baked.

I also form in suitable patterns split sand molds 29 which contain between their halves the U-shape passages 30 which form the 115 handles 9, as shown in Figs. 10 and 11. These molds are inserted in the apertures of the base F which were formed by the wooden blocks 27, with the open ends of the U-shape passages joining the print left by 120 the plate 19. I prefer to make such split molds narrower than said apertures, so that small spacer blocks 31 of sand may be used to shift the position of the handle molds, as may be desired in the particular furnace 125 practice.

When the various parts are ready I mount the sand core E upon the drag A by stepping the base F in said drag. I then put the portion D of the sand mold, contained 130

in the cheek B down over the core E and bolt the cheek to the drag, the lower end of the sprue registering with the gate 28. I then place the sand nose mold D' down over 5 the upper end of the core E and bolt the cope C to the cheek B.

The flask is now assembled for pouring, and the metal is introduced downwardly through the sprue and rises within the mold 10 until the same is filled as will be indicated by the riser passages.

When the metal is set and sufficiently cooled, the bolts 2 are removed and the cope and cheek lifted from the drag, exposing the 15 cast bosh plate, which is then removed, the sand knocked out of its interior and the gate and risers ground off. The ports 6, 7 and 8 are then threaded and the plate is completed.

20 It is evident from the foregoing that my improved process enables me to shorten the time required in and the expense of the casting of bosh plates, and also enables me to produce a superior plate having no unhomo- 25 geneous anchors embedded therein and no wire holes in the water baffles or internal partitions.

Although, for the sake of clearness of description, I have minutely described the 30 embodiment of my invention shown in the drawings, I do not wish to limit myself thereby, but claim broadly:

1. In a mold for casting furnace bosh plates in a vertically disposed position, the 35 combination of a flask, a sand base contained in said flask, a sand core supported by and in spaced relation above said sand base by means of sand necks integral with both said sand base and sand core and which 40 necks form the water ports in the front wall of the finished bosh plate, and a sand mold surrounding and enclosing said sand core and resting on said base, said sand mold being made separate from said sand base 45 and sand core, as and for the purpose described.

2. In a mold for casting furnace bosh plates in a vertically disposed position, the combination of a flask, a sand base contained 50 in the drag of said flask, a sand core supported by and in spaced relation above said sand base by means of sand necks integral with both said sand base and sand core and which necks form the water ports in 55 the front wall of the finished bosh plate, and a sand mold surrounding and enclosing said sand core and resting on said base, said sand mold being formed separately from said sand base and sand core, and said sand 60 mold being provided with a vertical sprue whose lower end is connected to the space between said sand base and sand core, as and for the purpose described.

3. In a mold for casting furnace bosh 65 plates in a vertical disposed position, in

combination with a flask comprised of a drag, a cheek and a cope, a sand base fitting in said drag, a sand core vertically supported by and in spaced relation above said sand base by means of sand necks integral 70 with both said sand base and sand core and which necks form the water ports in the front wall of the finished bosh plate, a two-part sand mold surrounding and enclosing said core and resting on said base, said sand 75 mold being comprised of a body portion contained in the cheek and a separately formed nose portion contained in the cope, and a sprue for the admission of the metal to the interior cavity of said sand mold, 80 as and for the purpose described.

4. In a mold for casting furnace bosh plates in a vertical disposed position, in combination with a flask comprising a drag, a cheek and a cope, a sand base fitting in said drag, a sand core vertically supported by and in spaced relation above said sand base by means of sand necks integral with both 85 said sand base and sand core and which necks form the water ports in the front wall 90 of the finished bosh plate, and a two-part sand mold surrounding and enclosing said sand core and resting on said base, said sand mold being comprised of a body portion contained in the cheek and a nose portion 95 contained in the cope, and said two-part sand mold being provided with a vertical sprue communicating at its bottom with the space between said sand base and sand core, as and for the purpose described.

5. The method of forming a sand mold in two parts by separate compacting operations for the purposes described which consists in mounting a two part core pattern upon a support inclosing the lower portion of said pattern in a vertically disposed cheek, placing a plate over the top of said cheek, positioning the nose portion of said pattern on said plate and surrounding the same with a cope, filling said cope with 100 sand, and compacting the same; then removing said plate and cope and its contents and filling the cheek with sand and compacting the same.

6. The method of forming a sand mold in two parts by separate compacting operations for the purposes described which consists in mounting a two part core pattern and a sprue pattern on a support, placing a cheek down over the same, placing a plate over the top of said cheek, said plate being provided with an aperture for the upward extension of said sprue pattern, positioning the other portion of the core pattern on said plate, placing a cope around said last-named portion of the core pattern and the upper end of said sprue pattern on said plate, filling said cope with sand and compacting it, lifting said plate and cope with its contents off of said cheek, filling said 115 120 125 130

cheek with sand and compacting the same.

7. In a mold for casting furnace bosh plates in a vertically disposed position, the combination of a flask, a sand base contained in said flask, a sand core supported by and in spaced relation above said sand base whereby a space is provided for the entrance of metal between the sand base and the sand core to form the front wall of the bosh plate, spaced apart supports extending upwardly from said sand core to said sand base, said supports forming the cores for the water passages through the front wall of the bosh plate, and a sand mold surrounding and enclosing but out of contact with said sand core and resting on said sand base, as and for the purpose described.

8. In a mold for casting furnace bosh plates in a vertically disposed position, the combination of a flask, a sand base contained

in said flask, a sand core supported by and in spaced relation above said sand base whereby a space is provided for the entrance of metal between the sand base and the sand core to form the front wall of the bosh plate, spaced apart supports extending upwardly from said sand core to said sand base, said supports forming the cores for the water passages through the front wall of the bosh plate, a sand mold surrounding and enclosing but out of contact with said sand core and resting on said sand base, and said sand mold being provided with a vertical sprue communicating at its bottom with the space between the sand base and the sand core, as and for the purpose described.

Signed at Pittsburgh, Pa., this 3rd day of November, 1919.

JAMES SMITH.
